UNITED STATES PATENT OFFICE.

CHARLES A. MASLINE, SR., OF PORT CHESTER, NEW YORK.

DESIGN FOR A FLAG.

57,366.

Specification for Design.

Patented Mar. 15, 1921.

Application filed July 27, 1920. Serial No. 399,401. Term of patent 7 years.

To all whom it may concern:

Be it known that CHARLES A. MASLINE, Sr., a citizen of the United States, residing at Port Chester, Westchester county, New York State, has invented a new, original, and ornamental Design for a Flag, to be known as "World War Honor Flag," of which the following is a specification, reference being had to the accompanying drawing and model, forming part thereof.

The figure is a plan view of a flag showing my new design, the thirteen horizontal stripes are alternate red, white and blue; the stars, 48 in number are gold in a silver field.

I claim:

The ornamental design for a flag as shown.
